UNITED STATES PATENT OFFICE.

JOHN H. WEYANDT AND ANDREW E. WEYANDT, OF BOWERSTON, OHIO.

PLUMB AND LEVEL.

SPECIFICATION forming part of Letters Patent No. 716,603, dated December 23, 1902.

Application filed May 16, 1902. Serial No. 107,598. (No model.)

To all whom it may concern:

Be it known that we, JOHN H. WEYANDT and ANDREW E. WEYANDT, citizens of the United States, residing at Bowerston, in the county 5 of Harrison, State of Ohio, have invented certain new and useful Improvements in Plumbs and Levels; and we do hereby declare the following to be a full, clear, and exact description of the invention, such as will enable others 10 skilled in the art to which it appertains to make and use the same.

This invention relates to combined plumbs and levels; and it has for its object to provide a tool of this nature by means of which the 15 questions of whether or not a body is plumb or is level can be determined with accuracy, a further object of the invention being to provide a construction wherein the dial may be read from either side of the tool or instrument.

Other objects and advantages of the invention have reference to details of structure and will be understood from the following description.

25 In the drawings forming a portion of this specification, and in which like numerals of reference indicate similar parts in the several views, Figure 1 is a side elevation of an instrument embodying the present invention. 30 Fig. 2 is an upper edge view or top view of the instrument. Fig. 3 is a vertical section taken transversely through the instrument. Fig. 4 is a section on line 4-4 of Fig. 1.

Referring now to the drawings, the present 35 instrument comprises a body portion consisting of three layers 5, 6, and 7, of wood, these layers being disposed with the grain of each layer transverse to the grain of the adjacent layers, the parts being held together by means 40 of screws 8 and the result being a structure that will not warp. In the central layer 6 of the body is formed a transverse circular opening 9, and in the layers 5 and 7 are formed transverse segmental openings 10 and 11, 45 which register with the opening 9 and have the same radius as said circular opening. Through the upper edge or top of the body is formed a circular opening 12, which communicates with the transverse openings, as 50 shown, said opening 12 being covered by a glass 13, which is held in the plate 14, which in turn is seated in the upper face of the body

to lie flush therewith. Centrally of the opening 9 and in the upper portion thereof is secured a segmental dial-plate 15, the uppermost point of which is marked "Zero," while the degrees are marked at each side thereof.

In the inner faces of the layers 5 and 7 are secured the plates 16 and 17, having the bearings 18 and 19, which are coaxial with the plate 15 and the openings in the layers of the body, and in the bearings 18 and 19 are engaged the conical ends of the rock-shaft 20, from which depends the weight of the pendulum 21, while projecting from the opposite side of the shaft 65 are the spaced fingers 22 and 23, which lie at opposite sides of the plate 15 and which are designed to point to corresponding portions of the opposite faces of the plate, the weighted pendulum serving to hold the fingers at all 70 times in a vertical plane. Secured to the plate 14 diametrically of the opening 12 and below the glass 13 is a web or wire or thread 24, which is the line with which the fingers or indexes register when the instrument is lying 75 with its upper face level and incidentally with its lower face level.

The openings in the layers 5 and 7 are countersunk to receive segmental glass plates 26, which are held in place by means of metal 80 bands 27, these glass plates acting to protect the interior mechanism, while permitting sight of an index from either side of the instrument.

To permit the use of the instrument for determining when the body is plumb, a recess is formed in one face of one end of the body, and in this recess is pivotally mounted the shaft 30, which carries the index 31 and the pendulum 32, the shaft being mounted in 90 bearings in the bottom of recess and in the plate 33, respectively, said plate 33 being secured over a portion of the recess in such position as to cover the weight and expose the index, and on the inner face of the plate are 95 formed the stops 34, which lie in the path of movement of the weight or pendulum to limit the movement of the index. A plumb-point 36 is marked on the face of the body and with which the free end of the index registers when 100 the instrument is held vertical. The recess is provided with a glass plate 37, which covers that portion in which the index operates, so that the index may be seen.

It will be understood that in practice modifications of the specific construction shown may be made and any suitable materials and proportions may be used for the various parts without departing from the spirit of the invention.

What is claimed is—

A leveling instrument comprising a body including a central layer and side layers, said central layer having a transverse cylindrical opening therethrough and the side layers having segmental openings therethrough regis-

tering with and coaxial with the first-named opening, a weighted index pivotally mounted in the first-named opening, a dial in coöperative relation to the index and transparent closures for the openings in the side layers. 15

In testimony whereof we affix our signatures in presence of two witnesses.

JOHN H. WEYANDT.

ANDREW E. WEYANDT.
